(57) **CLAIM**

The ornamental design for an apparatus for reading an optical disc, as shown.

DESCRIPTION

FIG. 1 is a perspective view of the top, front and left side of an apparatus for reading an optical disc showing our new design;

FIG. 2 is a perspective view of the bottom, front and right side thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.
